DESIGN FOR A GAS BURNER

Milton H. Smith, Long Beach, Calif., assignor to
The Oil Tool Corporation, Long Beach, Calif., a corporation of California

Application May 9, 1939, Serial No. 84,885

Term of patent 7 years

To all whom it may concern:

Be it known that I, Milton H. Smith, a citizen of the United States, residing at Long Beach, in the county of Los Angeles and State of California, have invented a new, original, and ornamental Design for a Gas Burner, of which the following is a specification, reference being made to the accompanying drawing, forming part thereof.

The figure is a perspective view of a gas burner showing my new design.

I claim:

The ornamental design for a gas burner, as shown.

MILTON H. SMITH.
